UNITED STATES PATENT OFFICE

172,466

TOY DOG

Alfred Felden, Brooklyn, N. Y., assignor to Gloria Toy Company, Inc., New York, N. Y., a corporation of New York

Application June 3, 1953, Serial No. 25,299

Term of patent 7 years

(Cl. D34—2)

To all whom it may concern:

Be it known that I, Alfred Felden, a citizen of the United States, residing at Brooklyn, county of Kings, State of New York, have invented a new, original, and ornamental Design for a Toy Dog, of which the following is a specification, reference being had to the accompanying drawing, forming a part thereof.

In the drawing:

Fig. 1 is a front perspective view of the design for a toy dog.

Fig. 2 is a side elevation of the design for a toy dog.

Fig. 3 is a rear elevation of the design for a toy dog.

I claim:

The ornamental design for a toy dog, substantially as shown.
